UNITED STATES PATENT OFFICE.

HENRY ROREBECK, OF PARMA, ASSIGNOR TO CHARLES E. COATES, OF SPENCERPORT, NEW YORK.

HALTER.

SPECIFICATION forming part of Letters Patent No. 288,595, dated November 13, 1883.

Application filed May 18, 1883. (No model.)

To all whom it may concern:

Be it known that I, HENRY ROREBECK, of Parma, Monroe county, New York, have invented a certain new and useful Improvement 5 in Halters; and I do hereby declare that the following is a full, clear, and exact description of the same, reference being had to the accompanying drawings, in which—

Figure 1 is a perspective view of the halter. 10 Fig. 2 is a side elevation of the same. Figs. 3 and 4 are detail views, showing portions of the rope.

My improvement relates to rope halters having leather head and nose pieces, the body of 15 the halter being made from a single piece of rope formed in a peculiar way, as hereinafter more fully described.

In the drawings, A shows the leather head or crown-piece, which fits over the head back 20 of the ears, and is provided with a buckle, a, by which it can be taken up or let out.

B is the nose-piece, also made of leather, and consisting of a simple strap, to which the rope is attached, as hereinafter described.

25 C is the rope which forms the body of the halter and also the stall or hitching end. This rope is arranged as follows: The end b of the rope is sewed or otherwise securely fastened to one end of the leather nose-piece B. The 30 rope is then carried up through a loop, d, at one end of the leather head-piece, forming the length 1. After passing the loop d the rope extends across and through the loop d', at the other end of the head-piece, forming the 35 length 2, which fits under the throat. From the loop d' the rope passes down and is attached to the other end of the nose-piece, forming the length 3, which corresponds with length 1. Thence the rope is carried out beyond 40 the end of the nose-piece and turned to form the loop 4. Thence it is carried in and attached to the end of the nose-piece. Thence it is carried upward and backward, forming the length 5; is passed around the length 2, 45 forming a loop, 6, thereon, and thence is carried down and attached fast to the end of the nose-piece, where the rope first started, forming the length 7, similar to length 5. Thence

the rope passes across from one end of the nose-piece to the other, forming the length 8, 50 and thence the loose end passes through the loop 4 and extends outward, forming the stall or hitching end 9.

Halters have before been made with leather head and nose pieces and with a rope body in 55 a single piece. Such I do not broadly claim.

By the peculiar form of the rope, as above described, the length 2 is brought under the throat and is made self-adjusting thereto, fitting closely, but without undue pressure, being stayed by the two bights 5 and 7, and held by the same so as not to choke the horse. It is self-adjusting, by reason of the head-piece sliding freely on the rope, so that the length 60 2 will always fit closely in place. By this 65 means the horse cannot slip the halter over his head, and no throat-leash is required. By this construction, also, the horse, in tightening the halter by drawing back, simply clamps 70 the nose-piece around his nose, without producing rubbing-friction and wearing the hair off, as is the case where both ends of the nose-piece are attached to two branches of a rope that runs through a noose. The device is simple, cheap, and effective.

Having described my invention, I claim— 75
1. A halter consisting of the head-piece A, nose-piece B, and rope C, said rope being in a single piece, consisting of the lengths 1, 2, 3, 5, 7, 8, and 9, and the loops 4 6, arranged to 80 operate in the manner and for the purpose specified.

2. In a halter consisting of the head-piece A, nose-piece B, and rope C, the lengths 1 2 3 of the rope forming the sides and the throat-piece, and the lengths 5 7 and loop 6, forming stays to the throat-piece, all combined to 85 operate in the manner and for the purpose specified.

In witness whereof I have hereunto signed 90 my name in the presence of two subscribing witnesses.

HENRY ROREBECK.

Witnesses:

E. C. BROWN,
JOHN McHUGH.
